UNITED STATES PATENT OFFICE.

PETER E. McSWEENEY, OF SPRINGFIELD, MISSOURI.

TRIPLE-VALVE-GRINDING MACHINE.

1,110,506.

Specification of Letters Patent. Patented Sept. 15, 1914.

Application filed May 7, 1914. Serial No. 836,994.

To all whom it may concern:

Be it known that I, PETER E. McSWEENEY, a citizen of the United States, residing at Springfield, in the county of Greene and State of Missouri, have invented certain new and useful Improvements in Triple-Valve-Grinding Machines; and I do declare the following to be a full, clear, and exact description of the invention, such as will enable others skilled in the art to which it appertains to make and use the same.

This invention relates to new and useful improvements in grinding machines and more particularly to a triple valve grinding machine and the primary object of the invention is to provide an improved machine of this character which will grind a plurality of valves at one and the same time, the valves being of various heights and designs.

Still another object of the invention resides in providing a machine which will permit the valves which are to be ground to be positioned vertically on the machine so that the oil and other matter which is received in the valve members will not accumulate in any one portion thereof but pass completely therethrough.

A still further object resides in providing a device which is simple and durable in construction, comparatively inexpensive to manufacture and one which will be very efficient and useful in operation.

With these and other objects in view my invention consists in the novel features of construction, combination and arrangement of parts as will be hereinafter referred to and more particularly pointed out in the specification and claims.

In the accompanying drawings forming a part of this application: Figure 1 is a front elevation of the machine. Fig. 2 is a side elevation thereof. Fig. 3 is a plan view of the same. Fig. 4 is a vertical transverse section therethrough as seen on line 4-4, Fig. 3.

In describing the invention I shall refer to the drawings in which similar reference characters designate corresponding parts throughout the several views and in which— 50 1 indicates a base or support such as the bed of a lathe or the like upon which are mounted in spaced relation to one another a pair of brackets 2 the upper ends thereof supporting bearings 3 in which is rotatably mounted a drive shaft 4. This shaft 4 is 55 of the crank shaft design, and has a drive

pulley 5 carried thereon which is adapted to receive power from any source (not shown). If, however, it is desired, the motor such as is often used on electric lathes may be connected directly to the shaft 4. Also mounted on the base or supporting member 1 in a plane forward of the plane of the supports or brackets 2 and in planes beyond the latter are the additional brackets 6 the latter extending upwardly to a plane some distance above the upper ends of the brackets 2. The upper portions of these brackets support bearings 7 in which is rotatably mounted a shaft 8. Adjustably connected on this shaft 8 is an arm 9 forming a crank thereon the same extending rearwardly over the shaft 4 and the rear end of said arm 9 has connection with a pitman 10 which also connects with the crank on said shaft 4. It will thus be seen that upon the rotation of the shaft 4, the shaft 8 will be oscillated in its bearings and a balancing weight 11 is provided on the crank arm 9 to aid in the actuation of the latter.

Supported on the base 1 and arranged in a plane above the plane of the upper face of the latter is a stationary table 12, the same being supported by means of brackets 13. The table 12 is provided adjacent its inner edge with a plurality (four in number) of openings, the same being spaced one from the other for the longitudinal length of said table and mounted securely on the table to encircle these openings so that the bores thereof may register therewith are the guide sleeves or bearings 14. Slidably mounted in the guide sleeves or bearings to operate loosely therethrough and through the table 12 are the vertically reciprocating rods or arms 15.

Adjustably connected at predetermined points on the shaft 8 are the outstanding arms 16, to the outer ends of which are adjustably secured the clamping members or the like 17. Pivots connected to the clamping members are the upper ends of links 18 the opposite ends of said links being pivotally connected respectively to the upper ends of said sliding or reciprocating rods or arms 15. It will thus be seen from this construction that upon the oscillation of the shaft 8 in its bearings, the slide rods 15 will be reciprocated in their respective bearings 14 to carry out the object of the device as will be hereinafter and more particularly set forth. The stationary table 12

is also provided adjacent its forward edge and in alinement with the openings adjacent the rear edge thereof with additional openings indicated as 19 in the drawings and 5 the upper face of this table surrounding the openings is offset to provide seats 20 which receive master chucks 21 therein. These master chucks 21 are held in place in the seats or recesses 20 by means of the adjustable clamping members 22 which are 10 carried on the upper face of the table 12 as clearly shown in the drawings, and the triple valves are adapted to be threaded into engagement with these chucks whereby 15 to permit the same to be properly ground, which is the primary object of the device.

Adjustably secured to the reciprocating arm 15 at predetermined points thereon above and below the table 12 are the additional outstanding and forwardly projecting arms 23 and 24 respectively. Suitably engaged with the outer ends of the lower arms 24 are the adjusting screws 25 while 20 adjustably secured to the outer ends of the upper arms 23 are the vertically extending rods or arms 26 and these screws 25 and the arms 26 are adapted to be adjusted so as to securely retain therebetween the pistons of the triple valves when the latter are 25 properly seated on the table, it being understood that the pistons of said valves operate 30 through the openings 19 in said table 12. Through this medium, it will be seen that the pistons of the triple valves will be 35 reciprocated in the latter and the desired grinding of said valves will result therefrom.

When triple valves of an air brake system become defective, the same are removed 40 and the triple valve pistons are removed from the valve body by removing the cylinder cap from the latter. The slide valve and packing ring are then removed from the triple valve piston and said slide valve placed on a face plate upon which fine emory 45 has been sprinkled and through this medium the slide valve is faced off. The valve seat bush which has a groove therein for the reception of the slide valve is then faced 50 with a safety parallel file. A new packing ring is then fitted snugly to the packing ring bush and the latter replaced in position. The slide valve is then replaced on the triple valve piston and a small amount 55 of grinding compound is placed on said slide valve. The triple piston is then replaced in the triple valve and a small amount of oil placed around the triple piston bush whereupon the triple valve is 60 threaded into place in the master chuck on this machine. The stroke of the triple valve machine is then adjusted to fit the various sizes and styles of triple valves used. It will be understood that in the 65 description above regarding the removal and

grinding of the various parts of the triple valve, a well known type of Westinghouse triple valve is assumed to be in use. In the use of other forms and styles of triple valves, the operation is quite similar and 70 the principle the same.

From the foregoing it will be seen that I have provided a simple, inexpensive and efficient means for carrying out the objects of the invention, and while I have particularly described the elements best adapted to perform the functions set forth, it is obvious that various changes in form, proportion and in the minor details of construction may be resorted to without departing from the 75 spirit or sacrificing any of the principles of the invention.

Having thus described my invention what I claim is:

1. In a machine of the character described, a stationary support having a series of openings arranged therein at predetermined intervals, a shaft mounted for oscillation above said support and in longitudinal relation thereto, means to oscillate 85 said shaft, arms projecting from the latter, rods guided through the openings in said table and having a link connection with said arms, supplemental arms disposed in spaced relationship upon said rods above and below 90 said table, and means on said supplemental rods for the connection of additional members thereto.

2. In a machine of the class described, a table having openings arranged therein at predetermined points, a shaft mounted for oscillation thereabove, means for oscillating said shaft, a plurality of arms projecting forwardly therefrom and adjustably connected thereto, rods guided through the 105 openings in said table and having connection with the outer ends of said arms to reciprocate with respect to the table upon the oscillation of said shaft, additional arms carried on said rod above and below said table and means on said additional rods for the connection of additional members thereto.

3. In a machine of the class described, a stationary table having a plurality of openings arranged at predetermined intervals therein, a shaft mounted for oscillation thereabove, means for oscillating said shaft, a plurality of arms adjustably connected with said shaft and projecting forwardly 115 therefrom, a plurality of rods guided through the openings in said table, guide sleeves mounted on said table around the openings therein and receiving said rods therethrough, linking members suitably 120 connecting the upper ends of said rods with the outer ends of said arms on the oscillating shaft, whereby to reciprocate said rods as the shaft oscillates, and means mounted on said rods for the connection of additional 125 130

members thereto to reciprocate with the same.

4. In a machine of the class described, a table having a plurality of openings arranged at predetermined intervals therein, a shaft mounted for oscillation thereabove, means for oscillating said shaft, arms adjustably connected with said shaft and projecting forwardly therefrom, a plurality of rods loosely disposed through the openings in said table and adjustably connected to the outer ends of said arms, an additional arm carried on each of said rods above and below said table, and adjustable means carried on the ends of said additional arms for the support of an additional member therebetween for reciprocation with said rods.

5. In a machine of the class described, a stationary table having a plurality of openings arranged at predetermined intervals therein, a guide sleeve vertically disposed above each of said openings, a shaft mounted for oscillation thereabove, means for oscillating said shaft, a plurality of arms adjustably connected to said shaft and projecting forwardly therefrom, rods movable vertically through said sleeves and the openings in said table, means for pivotally and adjustably connecting the upper ends of said rods to the outer ends of said arms, a pair of additional arms connected to each of said rods, one being disposed above and the other below said table, and adjusting means connected to the outer end of each of said additional arms whereby to secure an additional member between each pair thereof for reciprocation with the rod carrying the same.

6. In a device of the class described, a stationary table having a plurality of openings arranged at predetermined intervals therein, a vertically disposed guide sleeve arranged above each of said openings, a shaft mounted for oscillation thereabove, means for oscillating said shaft, a plurality of arms adjustably connected with said shaft and projecting forwardly therefrom, a plurality of rods movable vertically through the guide sleeves and the openings in said table, means for adjustably and pivotally connecting the upper ends of said rods with the outer ends of said arms, a pair of additional arms adjustably connected to each rod, one arm being disposed above and the other below said table, and vertically adjustable means at the outer end of each of said additional arms whereby to secure an additional member between each pair of said additional arms for reciprocation with each of said rods.

7. In a machine of the class described, the combination with a stationary table having a pair of rows of spaced apart openings therein arranged in planes adjacent the front and rear edges of the same, and means in connection with said table adjacent the forward row of openings therein for seating members thereon; of a shaft mounted for oscillation above said table, means for oscillating said shaft, a plurality of arms adjustably connected with said shaft and projecting forwardly therefrom, a plurality of vertically movable rods disposed through the row of openings adjacent the rear edge of the table, means pivotally and adjustably connecting the upper ends of said rods to the outer ends of said arms, a pair of additional forwardly extending arms adjustably connected to each rod, one above and one below said table, and means adjustably connected with the outer ends of the pair of additional arms for reciprocation through the openings adjacent the forward edge of said table.

8. In a machine of the class described, the combination with a stationary table having a pair of rows of spaced apart openings therein, each row being disposed respectively adjacent the forward and rear edges of said table, and means on the table for securing members thereon in connection with the openings at the front edge of said table; of a shaft mounted for oscillation above said table, means for oscillating said shaft, a plurality of arms adjustably connected with said shaft and projecting forwardly therefrom, the outer ends of the arms terminating in a plane forward of the plane of the rear row of openings in said table, a plurality of rods vertically movable through the last mentioned row of openings, linking members pivotally connected to the upper ends of said rods and adjustably connected to said arms adjacent the outer ends thereof, a pair of additional arms adjustably connected to each rod, one above and one below said table, and means in connection with the outer ends of said additional arms for adjustably connecting an additional member thereto for reciprocation through the openings adjacent the front edge of said table.

In testimony whereof I have hereunto set my hand in presence of two subscribing witnesses.

PETER E. McSWEENEY.
